UNITED STATES PATENT OFFICE.

BENNIE W. BURDETT AND FREDDIE M. BURDETT, OF SIMPSONVILLE, SOUTH CAROLINA.

SUPPORTING-PLATE FOR VEHICLE-BODIES.

No. 895,537.

Specification of Letters Patent. Patented Aug. 11, 1908.

Application filed September 5, 1907. Serial No. 391,486.

To all whom it may concern:

Be it known that we, BENNIE W. BURDETT and FREDDIE M. BURDETT, citizens of the United States, residing at Simpsonville, 5 in the county of Greenville and State of South Carolina, have invented a new and useful Supporting-Plate for Vehicle-Bodies, of which the following is a specification.

This invention relates to an improvement in vehicle bodies and has for its object to provide a simple and efficient means for preventing the bodies of carriages, especially buggies, and the like, from breaking loose at the corners and dropping down, which often happens when the sides of a buggy are subjected to more strain than they are intended to resist. The extra strain thus received causes the sides to break away from the screws at the corners and droop down over the bottom. 20 To avoid this trouble and provide a strong and substantial vehicle is therefore the purpose of this invention.

In the accompanying drawing:—Figure 1 is a perspective view of a corner of a buggy bed as seen from below with the invention applied. Fig. 2 is a cross sectional view through one of the side sills of a buggy bed and attached parts to show more clearly the object of the invention. Fig. 3 is a perspective view of the plate embodying the invention, detached.

Similar reference numerals are used throughout to designate like parts.

The buggy bed or body comprises in its 35 construction sides 2, side sills 3 to which said sides are screwed, front and rear ends 4, of which only the rear end is shown, and a bottom 5, all of which parts are well known in the art. End spring buggies, for which this 40 invention is more particularly designed, have attached to each corner a hanger 6, which hangers support the body on the springs. Each hanger 6 extends longitudinally beneath the body some distance from the end 45 thereof and is secured to said body by bolts 7 passing therethrough and through the side sill 3. The outer end of the hanger is bent upward in any well known manner to rest on a spring.

50 Referring to Fig. 2, it will be seen that the lower edge of the side 2 is in the plane of the under side of the sill 3 as is also the case with the end 4 which is fastened, as usual, to the side 2 through the medium of a corner block 55 8. This fastening has not been found secure

in practice, and the side is liable to break away from the block and hang down beside the sill. To prevent such accidents and to make the carriage bed more rigid, metal plates 9 are applied to the under side of the 60 sills 3 between said sills and the hangers 6 at each corner of the body and secured by the bolts 7.

The plate 9 is flat and rectangular in outline, its length being about that of the under 65 body portion of the hanger, and its width equal to the combined width of the side 2 and the sill 3. These dimensions, it is to be understood, are only approximate, as they may be 70 changed to suit the character of vehicle for 75 which the plate is made. The plate when in place lies for its full length under the side 2 and gives the side efficient support from below so that the fastening means used for holding the side is relieved from the strain 80 and other abnormal conditions to which it is so often subjected. The outer edge 11 of the plate, as well as its outer end 12, are beveled inwardly from its upper face to render the plate invisible. Two slots 13 are 85 made in the plate which register with holes in the hanger. The slots 13 extend longitudinally of the plate 9, so that said plate may be adjusted to fit any form of end spring 90 buggy bed. Holes 14 are made in the plate 9 to receive small screws, nails, or the like, to hold said plate in position while the hangers are being attached. The screws or nails may be removed or allowed to remain in the plate.

We claim:—

The combination with a vehicle body including a bottom, a sill, and a wall, said sill being interposed between the wall and bottom; of a hanger extending under the sill, a 95 plate interposed between the hanger and the sill, opposite edge portions of the plate extending under and supporting the bottom and wall of the body, and means extending through the sill, plate and hanger for binding them together.

In testimony that we claim the foregoing as our own, we have hereto affixed our signatures in the presence of two witnesses.

BENNIE W. BURDETT.
FREDDIE M. BURDETT.
